US0D1091181S

(12) **United States Design Patent** (10) Patent No.: **US D1,091,181 S**
(45) Date of Patent: ** Sep. 2, 2025

(54) **TWO PIECE SUPPORT PILLOW SET**

(71) Applicants: **Shawn P. Higgins**, Huizhou (CN);
Ignacio Navarro De Corcuera,
Larnaca (CY)

(72) Inventors: **Shawn P. Higgins**, Huizhou (CN);
Ignacio Navarro De Corcuera,
Larnaca (CY)

(73) Assignee: **Cross Innovations, LLC**, Cheyenne,
WY (US)

(**) Term: **15 Years**

(21) Appl. No.: **29/853,077**

(22) Filed: **Sep. 13, 2022**

(51) LOC (15) Cl. **06-13**

(52) U.S. Cl.

USPC **D6/601**

(58) **Field of Classification Search**

Daniel S. Bretzius

(57) **CLAIM**

The ornamental design for a two piece support pillow set, as shown and described.

DESCRIPTION

FIG. 1 is a top, front, and right perspective view of a two piece support pillow set showing our new design;

FIG. 2 is a top, front, and left perspective view thereof;

FIG. 3 is front view thereof;

FIG. 4 is a rear view thereof;

FIG. 5 is a right view thereof;

FIG. 6 is left view thereof; and,

FIG. 7 is a bottom view thereof.

1 Claim, 7 Drawing Sheets
